UNITED STATES PATENT OFFICE.

JOHN VANES, OF BRAZIL, INDIANA.

BOILER-FRONT.

SPECIFICATION forming part of Letters Patent No. 673,101, dated April 30, 1901.

Application filed October 3, 1900. Serial No. 31,917. (No model.)

To all whom it may concern

Be it known that I, JOHN VANES, a citizen of the United States, residing at Brazil, in the county of Clay and State of Indiana, have invented certain new and useful Improvements 5 in Boiler-Fronts; and I do hereby declare the following to be a full, clear, and exact description of the invention, such as will enable others skilled in the art to which it appertains 10 to make and use the same.

My invention relates to improvements in steel or wrought-iron boiler-fronts, and is more especially adapted to stationary boilers or steam-generators.

15 The object of my invention is to produce a boiler-front which is lighter, cheaper, and more durable than those now in general use; also, one that will not warp or crack, while at the same time it is very ornamental; also, 20 to compensate for the contraction and expansion in a very simple manner; furthermore, which can be quickly set up in place, as well as taken down, and finally can be produced of thinner material than heretofore employed 25 and still be stronger than the ordinary cast-iron fronts.

With these objects in view my invention consists of a boiler-front rolled out of one, two, or more pieces or parts bolted together 30 and provided with beads or molding, thereby strengthening it and making it ornamental; also, to produce an expansion-joint in the front to compensate for expansion and contraction, and finally it consists in certain 35 details of construction and novel arrangement of parts, as will be more fully described hereinafter and specifically pointed out in the claims, reference being had to the accompanying drawings, in which—

40 Figure 1 represents a front elevation of my improved boiler-front. Fig. 2 is a cross-section on line $x-x$ of Fig. 1. Figs. 3 and 4 are detail views of a modified form of expansion-joint. Fig. 5 is a view of the expansion-joint 45 on an enlarged scale.

In the drawings, A represents the main part of the front, made in this instance in two parts, which are united by an expansion-joint B and bolted or riveted together. Each side

of the front is stiffened, as well as ornamented, 50 by means of a bead E, and around the circular opening for the end of the boiler is arranged another bead d, having like functions as bead E. The fire-doors D and the ash-pit doors C are also made of wrought-iron or steel. 55 The openings in the front for said doors are curved inward around their edges, as shown at c c, stiffening them, while at the same time strengthening the front. The holes for the bolts employed to hold the parts together may 60 be slotted, as shown in Fig. 5 at e e, to allow the parts to crawl, when they are expanded or contracted by different degrees of temperature. On each side of the front is arranged a bead or molding E E, which serves to ornament, stiffen, and strengthen the front. If desired, lead or asbestos packing or its equivalents may be employed between the edges of the expansion-joint and the front to form a 65 perfectly-tight joint. If desired, two expansion-joints B B' may be employed, one on the inside and one on the outside of the front, although I desire to use the joint shown in Fig. 4. The lug b, forming the lower or bearing part of the hinges, may be provided with 70 studs that pass through the front and are secured on the inside by a nut or rivet.

An ornamental cornice may be secured to the top of the boiler-front, also made of wrought-iron or steel, to impart a finish to it, 80 and by adding smoke-box doors to the extension a full or flush front can be made.

I am aware that broadly expansion-joints are old and have been used in steam, hot-water, and other pipes, as well as for other purposes; also, that sliding joints in boilers are old, but never in connection with a boiler-front, and I therefore do not claim such broadly; but,

Having thus described my invention, what 90 I claim as new, and desire to secure by Letters Patent, is—

1. A boiler-front made of wrought-iron or steel, provided with an expansion-joint B, the beads E, E, at the sides and the bead d around the opening for the boiler, as shown and specified. 95

2. A boiler-front made of wrought-iron or

steel, provided with an expansion-joint, the beads E, E, at the sides, the bead d around the boiler-opening, and the openings for the doors curved around their edges, as shown 5 and set forth.

3. A boiler-front of wrought-iron or steel, provided with a vertical expansion-joint between the furnace-doors and a vertical ex-

pansion-bead at each side, as and for the purpose set forth.

In testimony whereof I affix my signature in presence of two witnesses.

JOHN VANES.
